US0D1036388S

(12) **United States Design Patent** (10) **Patent No.:** **US D1,036,388 S**
(45) **Date of Patent:** **** Jul. 23, 2024**

(54) **CONNECTOR**

(71) Applicant: **Molex, LLC**, Lisle, IL (US)

(72) Inventors: **Thomas R. Marrapode**, Naperville, IL (US); **Jesus Enrique Fung**, Westmont, IL (US); **Andrew Kolak**, Villa Park, IL (US); **Wenzong Chen**, Naperville, IL (US); **Sung-Ping Huang**, Hsinchu (TW); **Chih Chung Wu**, Hsinchu (TW); **Sheng-Pin Su**, Hsinchu County (TW); **Chien-Lang Tai**, Hsinchu (TW)

(73) Assignee: **Molex, LLC**, Lisle, IL (US)

(**) Term: **15 Years**

(21) Appl. No.: **29/837,002**

(22) Filed: **Apr. 29, 2022**

(51) LOC (14) Cl. **13-03**

(52) U.S. Cl.

USPC **D13/133**

(58) **Field of Classification Search**

USPC D13/120, 121, 133, 151, 154, 174, 184, D13/199

CPC H01R 13/00; H01R 13/40; H01R 13/41; H01R 4/00; H01R 4/70; H01R 4/71; H01R 4/48275; H01R 12/89; H01R 33/06

Assistant Examiner — Devin Kelly

(57) **CLAIM**

The ornamental design for connector, as shown and described.

DESCRIPTION

FIG. 1 is a front perspective view of connector showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depicting the remainder of the connector form no part of the claimed design.

1 Claim, 7 Drawing Sheets
